CLAIM

The ornamental design for a garden lamp having lantern with columns and filigreed surfaces, as shown and described.

DESCRIPTION

FIG. 1 is a perspective view from above of the garden lamp having lantern with columns and filigreed surfaces, in accordance with my design;

FIG. 2 is a left side elevational view of the garden lamp having lantern with columns and filigreed surfaces on a reduced scale, in accordance with my design, the right side being identical thereto;

FIG. 3 is a front side elevational view of the garden lamp having lantern with columns and filigreed surfaces on a reduced scale, in accordance with my design, the rear being substantially identical thereto;

FIG. 4 is a top plan view of the garden lamp having lantern with columns and filigreed surfaces, in accordance with my design; and,

FIG. 5 is a bottom plan view of the garden lamp having lantern with columns and filigreed surfaces, in accordance with my design.

The broken lines show the solar batteries and a photoresistor and are not considered part of the design claimed.
